SHUTTLECOCK

James E. Wolf, Altoona, Pa., assignor to R. S. L. Shuttlecocks Co., Ltd., Altoona, Pa., a corporation of Pennsylvania

Application December 3, 1956, Serial No. 625,858

8 Claims. (Cl. 273—106)

This invention relates to badminton shuttlecocks and more particularly to a novel head construction therefor.

An object of the present invention is to provide a shuttlecock having a novel head construction which provides the required weight of the head without destroying the resiliency of the head.

This is accomplished by providing weighting members or posts projecting from the interior surface of the hollow head and preferably axially of the head with the free ends of the weighting members in unconnected relation so that they are free to move and will not dampen or restrict the action of the head in play.

Preferably, the head is molded as a relatively thin shell of plastic material and can be formed integrally with the vane of the shuttlecock or as a separate head which is adapted to be connected to the vane. The weighting members can be formed integrally with the head and can be properly located within the head so that the required weight and resiliency of the head can be achieved.

Other features and advantages of the invention will be apparent from the specification and claims when considered in connection with the drawings in which:

Figure 1 is a side view of the shuttlecock.

Fig. 2 is a longitudinal sectional view of the shuttlecock taken along lines 2—2 of Fig. 1.

Fig. 3 is a sectional view of the head taken along lines 3—3 of Fig. 2.

Fig. 4 is a fragmentary sectional view showing a separate head connected to the vane.

As shown in the drawings, the shuttlecock of the present invention comprises a head portion 10 and a vane portion 11. The vane construction can be of any desired form. As herein illustrated the vane comprises an inner skirt 12 and an outer latticed skirt formed by stems 13 connected by cross ribs 14. The head, as shown in detail in Figs. 2 and 3, has a relatively thin wall 15 and is formed with a hemispherical bottom portion 16 which merges into a cylindrical upper portion 17 adapted to be connected to the skirt 12 of the vane. As shown in Figs. 2 and 3, the inner end of the head has projected from its interior surface a plurality of weighting members 18 herein illustrated as cylindrical posts which project inwardly of and are located within the head.

While the head may be made in any desired manner, in the preferred form of the invention it is molded of a suitable thermoplastic material, such as nylon, polyethylene or the like, and is provided on the outer surface of the hemispherical portion 16 with ribs 19 to provide the required friction surface. The weighting members or posts are formed integrally with the head and extend axially of the head. As shown in Fig. 2, they may be made of any desired diameter as may be required to produce the required weighting. They can be a solid post as indicated at 18a or a hollow post 18b, as illustrated in Fig. 2. Also, the posts may be located in any desired pattern such as in concentric circles as shown in Fig. 3.

2

A feature of the invention resides in the fact that the inner or free ends of the posts are unconnected so that the posts are free to flex when the head is struck in the play of the game of badminton and hence do not tend to restrict or dampen the action of the head.

The head and vane can be molded in one piece, as shown in Figs. 1—3 or the head can be molded as a separate element having a collar 17a at the upper end of the cylindrical wall 17 adapted to fit around a cooperating sleeve 12a on the inner skirt 12 of the vane as shown in Fig. 4.

Variations and modifications may be made within the scope of the claims and portions of the improvements may be used without others.

15 I claim:

1. A head for a badminton shuttlecock adapted to be connected to a vane portion comprising a hollow hemispherical end portion of resilient material having a short cylindrical portion adapted to be connected to said vane portion, and a plurality of weighting members of substantial cross section connected to the interior surface of the end portion to project inwardly therefrom with the inner ends thereof unconnected whereby the proper weighting is obtained without a reduction in the resiliency 25 of the head.

2. A head for a badminton shuttlecock adapted to be connected to a vane portion comprising a hollow hemispherical end portion of resilient material having a short cylindrical portion adapted to be connected to said vane portion, and a plurality of integral weighting posts connected to the interior of the end portion to project inwardly thereof with the inner ends thereof disposed within the head and being unconnected whereby 30 the proper weighting is obtained without a reduction in the resiliency of the head.

3. A head for a badminton shuttlecock adapted to be connected to a vane portion comprising a hollow hemispherical end portion of resilient material having a short cylindrical portion having a collar at the edge thereof adapted to be connected to said vane portion, and a plurality of spaced, integral weighting members connected to the interior surface of the end portion to project inwardly thereof with the inner ends thereof unconnected whereby the proper weighting is obtained 40 without a reduction in the resiliency of the head.

4. A molded plastic head for a badminton shuttlecock adapted to be connected to a vane portion comprising a thin walled body having a hollow hemispherical end portion and a short cylindrical portion adapted to be connected to said vane portion, and a plurality of spaced, integral weighting members molded integrally with the end portion to project inwardly thereof, with the inner ends of said members unconnected whereby the proper 50 weighting is obtained without a reduction in the resiliency of the head.

5. A molded plastic head for a badminton shuttlecock adapted to be connected to a vane portion comprising a thin walled body having a hollow hemispherical end portion and a short cylindrical portion adapted to be connected to said vane portion, and a plurality of spaced axially extending posts molded integrally with the end portion to project inwardly thereof with the inner ends of said posts unconnected, said posts providing 55 proper weighting of the head without a reduction in the resiliency of the head.

6. In a badminton shuttlecock having a head and a connected vane portion, the improvement wherein said head comprises a hollow hemispherical end portion of resilient material having a short cylindrical portion connected to the vane portion of the shuttlecock, and a plurality of spaced, integral weighting members connected 70

to the interior surface of the end portion to project inwardly thereof with the inner ends thereof unconnected whereby the proper weighting is obtained without a reduction in the resiliency of the head.

7. In a badminton shuttlecock having a head and a connected vane portion, the improvement wherein said head comprises a hollow hemispherical end portion of resilient material having a short cylindrical portion adapted to be connected to the vane portion of the shuttlecock, and a plurality of separate axially extending weighting members connected to the interior surface of the end portion to project inwardly thereof with the inner ends thereof disposed within said head and in unconnected relation whereby the proper weighting is obtained without a reduction in the resiliency of the head.

8. In a molded, one-piece plastic badminton shuttlecock having a head and a connected vane portion, the improvement wherein said head comprises a hollow thin-walled hemispherical end portion of resilient material having a

short cylindrical portion adapted to be connected to the vane portion of the shuttlecock, and a plurality of axially extending, annularly positioned weighting posts molded integrally with the interior of the end portion with the inner ends thereof unconnected and disposed within the head whereby the proper weighting is obtained without a reduction in the resiliency of the head.
